2 SHEETS—SHEET 2.

UNITED STATES PATENT OFFICE.

ROBERT H. JEFFREY, OF COLUMBUS, OHIO, ASSIGNOR TO THE JEFFREY MANUFACTURING COMPANY, OF COLUMBUS, OHIO, A CORPORATION OF OHIO.

MINING AND LOADING MACHINE.

1,322,113.

Specification of Letters Patent. Patented Nov. 18, 1919.

Application filed May 1, 1914. Serial No. 835,759.

To all whom it may concern:

Be it known that I, ROBERT H. JEFFREY, citizen of the United States, residing at Columbus, in the county of Franklin and 5 State of Ohio, have invented certain new and useful Improvements in Mining and Loading Machines, of which the following is a specification, reference being had therein to the accompanying drawing.

10 This invention relates to mining machines of the class adapted to dislodge the coal from its native bed and to remove it rearwardly of the machine to be loaded for transportation from the mine.

15 It is the especial object of this invention to provide a machine having cutting devices capable of the formation of a plurality of parallel, spaced apart, horizontal kerfs extending across the face of the vein, or to 20 be adjusted to form a series of parallel vertical kerfs in the said coal face, in combination with means to break down the coal between said kerfs and means to receive and remove the coal as it is broken down.

25 In the following specification and the accompanying drawings I have disclosed the preferred embodiment of my invention but I do not wish to be limited to the specific construction here illustrated as there may be 30 wide variation in the means employed without departure from the spirit of my invention.

Of the drawings Figure 1 is a side elevation of a mining and loading machine embodying my invention, the cutting mechanism being adjusted for horizontal cutting.

Fig. 2 is a plan view of the machine illustrated in Fig. 1.

Fig. 3 is a fragmentary sectional view 40 taken on the line III—III of Fig. 1.

Like numerals refer to similar parts in the several figures.

Referring to the drawings the numeral 1 indicates the bed frame which is adapted to 45 rest upon and slide over the floor of the mine. Attached to the bed frame are vertical posts 2 and 3 which support bearings 4 and 5 in horizontal alinement with each other. In these bearings is mounted a 50 sleeve 6 carrying at its inner end a yoke 7 provided with spaced apart bearings 8. In the bearings 8 are mounted sleeves 9 upon the extended ends of which are rotatably mounted other bearings 10. The bearings 55 10 are formed integral with a frame 11

having a plurality of inwardly extending cutter arms 12 and 12'. On the cutter arms 12 and 12' are provided suitable guide ways 17 in which travel the cutter chains 16 and 16'. The chains 16 and 16' are provided with renewable cutter bits 19 by which the coal is cut in the manner well understood in the mining machine art. Journaled in the sleeves 9 is a shaft 13 to which are secured the sprocket wheels 14 by which the cutter chains 16 and 16' are driven. Similar sprocket wheels 15 are mounted on vertical axes at the inner ends of the cutter arms 12 and these sprocket wheels engage and are driven by the cutter chains 16. The 60 numerals 18 indicate thin circular kerf cutters of considerably larger diameter than the sprocket wheels 15 to which they are concentrically attached. The kerf cutters 18 extend in planes parallel with the 65 sprocket wheels 15 and revolve with them around their vertical axes. As shown in Fig. 1 the cutter arms 12 extend only far enough to provide support for the sprocket wheels 15 and the kerf cutters 18, and the 70 cutter chains 16 serve the double purpose of driving the kerf cutters 18 and of providing the necessary clearance for the supporting arms 12 to permit the entry of the kerf cutters 18 into the coal body to a depth 75 80 equal to their full diameters. The lowermost cutter arm 12' is, preferably, not provided with a kerf cutter 18 but is elongated to extend into the coal to a depth equal thereto, and the cutter chain 16' is 85 adapted to form a kerf of considerably 90 greater width than the chains 16 for a purpose which will be hereinafter explained.

Attached to the frame 11 is an arcuate rack 52 which is engaged by a worm 51 95 mounted upon a horizontal shaft 49. The shaft 49 is journaled in suitable bearings 50 attached to the yoke casting 7 and is provided with a hand wheel 48 convenient to the hand of the operator. By the manipulation of the hand wheel 48 the cutter frame 11 and with it the cutter arms 12 and 12' may be rotated about the sleeves 9 to feed the kerf cutters laterally in an arcuate path to cut the coal. Attached to the 100 sleeve 6 is a spur gear 43 which is engaged by a gear wheel 44 fixed to a horizontal shaft 45. The shaft 45 is supported in suitable bearings 46 of the bed frame and is provided with a hand wheel 47 convenient 105 110

to the hand of the operator. By the manipulation of the hand wheel 47 the sleeve 6 and with it the yoke 7 may be rotated in the bearings 4 and 5 thereby adjusting the 5 cutters to operate in planes at any desired angle with the direction of the coal vein.

As previously stated the bed frame 1 is adapted to be moved in any direction over the floor of the mine, and any preferred 10 means may be employed to effect such movement. For purposes of illustration I have shown in the drawings well known devices for accomplishing the moving and guiding of the machine. The feeding mechanism 15 comprises a winding drum 31 mounted near the inner end of the bed frame upon a horizontal shaft 35. The shaft 35 is supported in suitable bearings 36 of the base frame and is connected by worm gearing 37, 37^a with 20 the power shaft 24 journaled in bearings in the bracket 25 on the main frame. Attached to and windable upon the drum 31 is a flexible cable 32, the free end of which is adapted to be connected to any suitable abutment 25 outside of the machine such as the jack 38. A suitable guide sheave 33 mounted in a swiveling caster 34 provides means for guiding the rope in any preferred direction, and additional guide sheaves may be attached 30 to the frame of the machine at any preferred point to effect further guiding of the feed rope in the manner which is well understood in the mining machine art. By the actuation of the winding drum 31 the feed 35 rope 32 will be tensioned to draw the machine toward the abutment 38, and by the judicious positioning of said abutment the kerf cutters may be fed longitudinally inwardly of the coal body, or they may be fed 40 laterally across the face of the vein, or the machine may be otherwise moved about the working place as desired. I have provided means to balance the strain of the cutting mechanism and the feed rope whereby the 45 desired angular relation of the machine to the coal face may be maintained. At the outer end of the main frame a retarding device comprising a drum 39 upon which is wound a cable 40 adapted to be attached to 50 a suitable abutment, such as the jack 41, at the rear of the machine. Friction mechanism 42 is provided to resist the unwinding of the rope 40 in the manner well understood in the mining machine art.

55 In the drawings the numeral 53 indicates an elongated conveyer frame which is adapted to extend along the right hand side of the main frame 1 to which it may be removably attached by suitable braces 54. Upon the 60 conveyer frame 53 is mounted conveying mechanism which is indicated as a whole by the numeral 55. This conveying mechanism may be of any preferred construction, that indicated in the drawings being of the well 65 known type having endless chains connected

together by suitable cross bar flights which engage the material to move it longitudinally of the conveyer frame. At the outer end of the conveyer frame 53 is mounted a head shaft 56 having suitable sprocket 70 wheels, not shown in the drawing, which engage the chains of the conveyer to actuate the conveyer flights in the manner well understood in the conveyer art. The head shaft 56 is provided with a sprocket wheel 75 57 connected with the driving sprocket 59 through a suitable driving chain 58. The driving sprocket 59 is carried by a horizontal shaft 60 journaled in a suitable bearing 61 mounted upon the main frame 1. 80 The shaft 60 is driven from the vertical shaft 24 through a bevel gear 62 which meshes with the bevel gear 26.

The conveyer frame 53 is formed with an inner horizontal portion positioned adjacent 85 the mine floor and adapted to extend into the kerf formed by the cutter chain 16' to receive the coal as it is broken down, and an outer upwardly inclined portion adapted to elevate the coal to a sufficient height to be delivered into suitable receptacles for transportation from the mine. Positioned above the inclined portion of the conveyer is a breaking down mechanism comprising a reciprocable pick 63 adapted to engage the coal 90 to break it down upon the conveyer. This breaking down mechanism may be any one of several well known constructions. For the purpose of illustration I have shown a pick actuating mechanism comprising an air 100 cylinder 64 having a longitudinally reciprocable piston to which the pick tool 63 is attached. The cylinder 64 is provided with the usual valve chamber 65 and is supplied with compressed air from any convenient 105 source of supply through a suitable air hose 66. The cylinder 64 is supported upon trunnions 68 which are journaled in trunnion bearings 69. To one of the trunnions 68 is secured a hand wheel 67 by which the operator may rotate the cylinder about the axis of the trunnions to vertically adjust the pick 63. The trunnion bearings 69 are supported upon slide ways 70 attached to the conveyer frame 53 and by the movement of the trunnion bearings on said slide ways the pick 63 may be longitudinally adjusted relative to the coal face.

The process of mining coal by means of the above described apparatus consists of 120 two distinct steps, the first being the formation of a plurality of spaced apart parallel kerfs extending horizontally across the coal face, and the second being the dislodgment and removal of the coal. To accomplish the 125 first of these steps the breaking down and conveying devices are detached from the main frame and the machine is moved to the right hand side of the room its longitudinal lines extending at right angles to the coal 130

face and the kerf cutters projecting toward the coal. By the manipulation of the hand wheel 47 the kerf cutters are adjusted to operate in horizontal planes, or planes parallel to the direction of the coal seam. The proportions of the parts are such that when so adjusted the cutter arm 12' will lie in close proximity to the line of the floor of the mine. The anchor jack 38 will then be positioned adjacent the coal face and the feeding mechanism actuated to move the machine bodily longitudinally inward to cause the cutters to enter the coal. When the kerf cutters have advanced to a sufficient depth the anchor jack 38 will be removed to a position at the left of the machine, and the anchor jack 41 adjusted at the right hand side of the machine as illustrated in Fig. 2. By the manipulation of the feeding and retarding mechanisms, in the manner well understood in the coal mining art, the machine will be moved laterally across the working face to produce a series of spaced apart kerfs extending across the face of the vein parallel with the floor of the mine.

After the completion of the first step of the process, as above described, the machine will be returned to the right hand side of the room and the breaking down and conveying mechanism attached in the position indicated in the drawings. By means of the hand wheel 47 the yoke 7 will be rotated through an angle of 90 degrees, placing the kerf cutters 18 in vertical planes. The anchor jack 38 will then be positioned adjacent the coal face and the machine moved longitudinally inward, causing the kerf cutters to form a plurality of vertical kerfs intersecting the horizontal kerfs previously formed and dividing the coal into rectangular blocks of convenient size for transportation. As the machine advances into the coal the receiving portion of the conveyer enters the lowermost kerf and the pick 63 may be actuated to engage the coal to break it down. The material thus dislodged will fall directly upon the conveyer by which it will be deposited in suitably positioned receptacles for transportation from the mine. If the height of the coal vein be greater than the diameter of the kerf cutters 18, the frame 11 may be oscillated vertically by the manipulation of the hand wheel 48 to extend the kerfs to the full height of the vein. Owing to the position and thickness of the cutter arm 12' and the cutter chain 16' the lowermost kerf in the horizontal series will constitute an extension of the mine floor and will afford sufficient clearance for the receiving portion of the conveyer. After the completion of the inward thrust, as just described, the machine may be withdrawn from the coal, moved a

suitable distance toward the left, and the operation repeated, the coal being thus dislodged and removed in successive increments 65 over the entire width of the face.

What I claim is:

1. In a mining apparatus, the combination with a bed frame adapted to be moved in any direction over the floor of the mine, of means to move said bed frame relative to the mine walls, a cutting mechanism comprising a plurality of cutters adapted to simultaneously form parallel spaced apart kerfs, means to adjust said cutting apparatus to 75 form a plurality of horizontal kerfs across the coal face or to form multiple vertical parallel kerfs in said coal face extending in a series across the mine room, means at the rear side of the cutting apparatus for breaking down the coal between the kerfs, and a conveyer movable with said bed frame and cutters adapted to receive and remove the coal as it is broken down.

2. In a mining apparatus, the combination with a bed frame adapted to be moved in any direction over the floor of the mine, of means to move said bed frame relative to the walls of the mine, cutting apparatus carried by the bed frame adapted to form a plurality of parallel horizontal kerfs across the coal face the lowermost of which is of relatively great vertical width, means at the rear side of the cutting mechanism to break down the coal between the kerfs, and conveying mechanism separably connected with the bed frame and adapted to be propelled thereby having a receiving part arranged to travel in the lowermost kerf to receive and remove the coal as it is broken down.

3. In a mining apparatus, the combination with a bed frame adapted to be moved in any direction over the floor of the mine, of means to move said bed frame relative to the walls of the mine, cutting apparatus comprising a series of parallel cutters and a cutter carrier adapted to be adjusted to cause said cutters to form a series of horizontal kerfs in the face of the vein and to then be adjusted to form a series of vertical kerfs in the said face, a supplementary mechanism adapted to be separably attached to the rear side of the bed frame and to move therewith comprising means to dislodge the coal between the kerfs, and a conveyer adapted to receive and remove the coal as it is broken down.

In testimony whereof, I affix my signature in presence of two witnesses.

ROBERT H. JEFFREY.
